UNITED STATES PATENT OFFICE

THEODORUS HENDRIK NAKKEN, OF BROOKLYN, NEW YORK, ASSIGNOR TO NAKKEN PATENTS CORPORATION, A CORPORATION OF DELAWARE

APPARATUS FOR PHOTOGRAPHICALLY RECORDING AND REPRODUCING SOUND

Application filed November 6, 1928. Serial No. 317,586.

This invention comprises means, a method and a system for illuminating a film for the recording and the reproducing of a photographic sound-record.

5 Heretofore it has been considered good practice to limit the portion of a moving film against which a beam of cooperating light is to fall by means of a minute slot in close proximity to the surface of the film 10 or in contact therewith. If the slot is open, dust clogging is troublesome. If the slot is one involving transparent material, light loss, cost and scratching are disadvantages. An object of my invention is to make possible 15 the limitation of the area of the film illuminating to a minute transverse line area in the order of 0.0005 of an inch wide while not employing any slot and leaving a relatively large area of the film exposed through 20 a sufficiently large window to permit a visible adjustment thereon of a light beam and eliminate all dust collecting difficulties. Previous attempts have been made to do away with the slot contiguous to the film, 25 but great difficulties to be surmounted are presented. Commercial practice requires that the entire space which can be devoted to the illuminating system be relatively small, namely in the order of a few inches 30 in length. Practical commercial sources of light must be a finite size for practical operation and to deliver any substantial candle power, and the shape of the primary source of light is difficult of accurate defining. In 35 addition to these difficulties more linear space than commercial limitations permit will be required to effect an optical reduction of the size of the usual primary light source to dimensions within the limits re- 40 quired for the illumination of the film to prevent distortion from overlap. If a shield provided with an accurately defined light orifice is interposed between a standard primary light source enclosed in the usual 45 bulb and an optical lens system for the purpose of focusing the image on the film, such slot cannot serve as a secondary light source of sufficient intensity for practical purposes, even though lenses of large di- 50 ameter are employed, because of the fact

that relatively far distant spacing apart from the primary light source constrains it to become in large part illuminated only by diffused light so far as much of the area of the lens is concerned. This undesirable 55 limitation is difficult to overcome by increasing the candle power of the primary light source without either using an impractically high candle power lamp or running a lower candle power lamp at excessive excitation to 60 shorten its life.

It is an object of my invention to overcome all of the aforementioned difficulties by novel means, a novel method and a novel 65 system.

More specifically, I propose to eliminate all trouble from light slots against the film by doing away with them altogether and leaving a relatively large area of the film exposed into a simple housing containing 70 my illuminating system. I provide definition and regular outline for the light image to be applied to the film by utilizing a secondary light source in the form of a slot formed in a shield located, instead of outside of the bulb of the electric lamp, actually 75 within the bulb in close proximity to the primary light source; I shape the orifice in this light shield in the desired form and with the desired degree of regularity, and 80 preferably in the form of a minute slot-like rectangle so that a reduction to one-half or three-quarter size of its image is sufficient reduction to define a light line of the necessary smallness for application to the film; 85 I utilize the normally relatively large size of the primary light source and arrange the spacing therefrom of the secondary light source and the positioning of an optical condenser so that although the orifice in my 90 shield is or actually defines the image which the optical system reduces, the optical system nevertheless receives rays of light in a direct straight line from the primary light source through the orifice to substantially 95 every point on the surface of the objective lens. By this expedient I not only employ and project and accurately definitely define a light image of small size, but provide for intense uniform illumination of a relatively 100

large objective lens and by it concentrate a large quantity of light in the form of a minute light image upon the film.

I realize, of course, that in exposing a moving film for purposes of forming a photographic sound-record, relatively less light is required than in supplying a light beam which must pass through the film, be modulated thereby, and as a modulated beam be transformed by my photoelectric amplifier system into current impulses corresponding to the modulations of the light beam. However, primary sources of light which may be modulated for purposes of making a photographic sound-record are inherently of less candle power or less light intensity than such a source as an incandescent tungsten filament. Heretofore I understand that it has been necessary, when not employing this invention, to excite such a modulable light source beyond a degree commensurate with reasonable life.

In carrying out the purposes of my invention I propose to employ novel forms of electric lamps of one type (preferably glow type) for recording, and of another type (preferably filament type) for reproducing. Common to both of these types I propose to employ a heat resisting opaque light shield 30 provided with a definitely defined orifice located within the usual glass bulb which serves to maintain the desired cooperative atmosphere for the primary light source. It is a further object of my invention to provide improved means combining primary and secondary light sources, both within a bulb and embodying in some instances filament type primary light sources and in other instances glow type primary light sources. 35 Further objects of my invention are to provide auxiliary means in connection with a lamp providing such primary and secondary light sources while permitting the escape from the bulb of some radiant energy in the form of light and heat to prevent the injurious action of such escaping energy.

The further object of my invention is to attain all the objects above recited except for any disadvantage which may arise from the employment of a so-called film slot, because the employment of my light system in connection with a film slot is feasible, although the limiting and defining functions of such film slot are not necessary. This thought may be expressed by stating that much of my invention is applicable to apparatus in which any kind of a film slot is present and does not require the provision of a relatively large exposed surface of the film.

The above and further objects of my invention will be set forth more in detail in the following claims which are directed to illustrative embodiments of my invention solely for purposes of illustration and not

limitation. These illustrative embodiments of my invention are described in the following specification in connection with the accompanying drawings which form a part hereof.

In the drawings, Fig. 1 is an illustrative diagrammatic showing of principles employed in my invention,

Fig. 2 is a diagrammatic showing illustrating the limitations reducing the intensity of illumination below that which is required when employing a secondary light source materially separated from the primary light source,

Fig. 3 is a diagrammatic vertical cross-section with parts shown in elevation of a preferred embodiment of my system for recording purposes,

Fig. 4 is a similar view of my system for reproducing purposes,

Fig. 5 is a vertical elevation with parts shown in section and with parts broken away of a preferred embodiment of my modulable primary and secondary light source lamp,

Fig. 6 is a side elevation thereof with parts shown in section,

Fig. 7 is a top plan view of the lamp with parts shown in dotted lines,

Fig. 8 is a view of the blank employed for the protection of a light shield for the structure of Figs. 5, 6 and 7,

Fig. 9 is a front elevation by itself of a preferred embodiment of my electric primary and secondary lamp with parts broken away and parts shown in elevation.

Fig. 10 is a side view of the same with parts in section through the plane of line X of Fig. 9, and

Fig. 11 is a plan view with parts shown in dotted lines of the structure of Figs. 9 and 10.

Referring particularly to Fig. 3, any usual light-proof housing 1 mounts any suitable driving and guiding mechanism for the film A. In the diagram, wheels 2 and 3 may be driving sprocket wheels or guiding sprocket wheels with the film driven uniformly by a mechanism not shown across guiding trackers 4 and 5. A large window B formed in the wall 1 exposes a relatively large area 6 of the film A to the interior of the light-proof hood C. The window B may be sufficiently large to preclude any trouble from collected dust. Or without losing any of the other advantages of my invention it may be a functionless film slot close against the film area 6, as described in my copending slot applications.

Within the hood C is mounted a relatively large optical condenser D which is shown adjustable upon the fixed standard 10 for purposes of focusing, should adjustment be desired. It is preferred, however, that in commercial apparatus fixed mount-

ings without adjustment be provided so as to render the same more nearly foolproof.

5 Mounted within an auxiliary light-proof hood E and having light access to the interior of hood C through a window 11 is a glow lamp F preferably provided with the usual four-pronged vacuum tube base 12 cooperating with a complementarily perforated socket plate 13 so as to insure the 10 proper positioning of the lamp. It is to be understood that the auxiliary hood E is removably attachable as by thumb screws not shown to the main hood C. The glow lamp F may have any suitable electrode construction for its two electrodes 14 and 15 provided the light glow serving as the primary source of light is directed towards the window 11. The heat resisting opaque shield G formed with a light orifice H preferably in the form of a minute rectangular slot of accurate dimensions is suitably in close proximity to the primary light source I, in this case the glowing area.

The spacing of the slot H and the size 25 of the primary light source, together with the size and spacing of the condenser D relatively to the film 6 is such that although it is the image of the slot H as a secondary light source which is focused at H' on the 30 film A, straight line beams 20 extend directly from the primary light source H itself to substantially every point on the surface of the condenser D. This is diagrammatically illustrated best in Fig. 1 35 viewed in contrast to Fig. 2, in which the limitations imposed by a different spacing are illustrated. In Fig. 2 a partition g is spaced outside of the bulb f in an attempt to employ its orifice h as a secondary light 40 source. Dotted lines 20' have been drawn to indicate the extent of or the limiting divergence which the orifice h defines for a direct straight line ray from the primary light source h to a condenser d. The relatively large condenser D of Fig. 1 has 45 been shown in dotted lines in Fig. 2. Thus in Fig. 2 the available light for projection as an image h' is less than one-ninth in Fig. 2 what it is in Fig. 1 because of the fact that the diameters of the objective d in Fig. 2 50 is one-third of the diameter of the objective D in Fig. 1. These diagrams well illustrate the qualitative difference brought about by the changes made possible by my 55 invention.

In Fig. 4 I have illustrated a slightly modified structure in which the auxiliary hood E' is within the hood C' and I have diagrammatically indicated the positioning 60 of the photoelectric cell j, the cathode body 25 of which is to be illuminated by the modulated beam 26.

In this construction the primary light source K is a spirally curled filament relatively positioned and of such a size as to

give the full direct line illumination by the beams 20 of the larged-sized condenser d. In this construction the window 11 instead of being in the wall of the hood C is in the wall of the auxiliary hood E', which of course is constructed of suitable material and with removable walls to prevent the mounting and replacement of the lamp L.

In the glow lamp structure, which I prefer to employ for recording purposes, shown in Figs. 5, 6, 7 and 8, the usual lamp bulb I of glass is provided and is preferably seated in the vacuum tube type of base 30 by means of cement 31 with usual sealed lead-in wires 32 and 33 leading to two prongs 34 and 35 of the four-prongs shown, four prongs being provided the better to insure proper seating when employing the usual vacuum tube socket as a mount. An opaque heat resisting light shield G is provided with an accurately formed minute light orifice H shaped preferably in the form of an open-ended envelope, the sides 40 and 41 of which are spaced apart one from the other and extend upwardly from the bottom lips 42 and 43 provided with notches 44, 45, 46 and 47 to accommodate the insulating tubes 48 and 49 which protect and insulate the upstanding supports 50 and 51. These tubes may be 50 constructed satisfactorily of isolantite, or of quartz, or of heat resisting vitreous material. It should be noted that one of the supports, such as 49, may be the lead-in 33 electrically connecting the inner electrode 60. In this construction, the shield H constitutes one of the electrodes, namely, the cathode, and functions as that in addition to its function as a shield. The anode 60 comprises spaced upstanding leaves 61 and 62. In assembling the parts, it is preferred to employ bendable ears 63 and 64 as shown in the drawings, the blanks shown in Fig. 8 being adapted to be bent along the dotted and dash lines into the form shown in Figs. 5, 6 and 7. The metal to be employed for the electrodes may be any suitable heat resisting metal, preferably nickel or chromium. In its functioning, the glow occurs within the space between the leaves 61 and 62 and constitutes the primary light source I. The secondary light source is the orifice H and it is to be noted, utilizes the full depth or end-on illumination of the globe between the leaves 61 and 62, the lamp being adapted for the use of beams extending upwardly from the showing in Figs. 5 and 6.

In Fig. 9 the usual electric lamp bulb 70 is employed mounted in the same base construction as that described for Figs. 5 and 6, but in this case leads 71 and 72 sealed in as is usual in good practice supply the spirally curled filament K with electric energy from the prongs 73 and 74. Mounted by suitable supports 75 and 76 is the cylindrical shield M of opaque heat resisting metal, such as

tungsten or chromium. In this shield is accurately formed a minute light orifice N preferably in the form of a minute rectangular slot serving as a secondary light source. Extending laterally outwardly from this secondary light source N are wings 80 and 81 which serve to cool the shield and also to shield any light which may escape from the cooling windows 82 and 83. In its formation, the shield M may be fabricated from a sheet metal stamping, which after it is welded together along the abutting edges 84 and 85, may be treated to true the dimensions of the slot N.

15 What I claim and desire to secure by United States Letters Patent is:

1. In the art of photographic sound recording and reproducing involving a moving film for the photographic sound-record, generating light from a primary light source of substantial size as to its smallest dimension and at a short distance from the moving film; maintaining a large area of said film uncovered on the side facing said light source and free from any film contacting part within the zone of any light beam from said source; forming a secondary light source in the shape of a minute substantially perfect short line of light contiguous to said primary light source by exposing a minutely slotted shield to the light spherically transmitted from said primary source, without interveningly focusing said primary light source upon said minutely slotted shield; focusing an image of said secondary source in its entirety in the form of a short transverse line upon said moving film by means of an optical condenser of large light collecting area and arranging the proximity of said minutely slotted shield to said primary source and the transverse dimensions of said primary source and the positioning and size of said condenser so as to maintain a commercially practicable small space occupied by said parts, a practicable small candle power for said primary light source by causing as a result of the aforesaid arrangement a direct straight line illumination of substantially every point upon the surface of said condenser from a light-emitting point of said primary source through said minutely slotted shield.

2. In an illuminating system for photographic sound-records, a film for the sound record; means for operatively moving said film; a walled enclosure for shielding said film against exposure to light and provided with a relatively large window exposing a relatively large area of the face of said film; an optical condenser opposite the exposed face of said film; a primary light source of too great a transverse size for its image to be focused in the form of a reduced image upon said film of sufficiently small dimensions for sound photographic recording or

reproducing; a minutely slotted light shield mounted in close proximity to said primary light source and free from the interposition of any focusing means between said primary light source and said minutely slotted light shield and forming by the minute slot provided therein a secondary light source capable of being focused by said condenser as a light image of the desired shape and dimensions upon said film for the purpose of photographically recording or reproducing a sound-record, said condenser, said primary light source and said secondary light source being spaced and proportioned to effect straight line illumination of substantially all of said condenser surface from said primary light source.

In witness whereof I have signed my name to this specification the 5th day of November, 1928.

THEODORUS H. NAKKEN.
